[57] CLAIM

The ornamental design for a belt pad, as shown and described.

DESCRIPTION

FIG. 1 is a top perspective view of a belt pad showing my new design;

FIG. 2 is a top plan view of the belt pad;

FIG. 3 is an elevational end view of the belt pad. The opposite elevational end view of the belt pad is the same as that of FIG. 3;

FIG. 4 is an elevational side view of the belt pad. The opposite elevational side view of the belt pad is the same as that of FIG. 4;

FIG. 5 is a bottom plan view of the belt pad.
